UNITED STATES PATENT OFFICE.

HORACE SEE, OF NEW YORK, N. Y.

DESIGN FOR A BOILER-DRUMHEAD.

SPECIFICATION forming part of Design No. 28,575, dated May 10, 1898.

Application filed February 11, 1898. Serial No. 669,985. Term of patent 14 years.

To all whom it may concern:

Be it known that I, HORACE SEE, of the city, county, and State of New York, have invented and produced a new and original Design for 5 Boiler-Drumheads, of which the following is a specification.

My design relates to a boiler-drumhead.

My design consists in the configuration of the boiler-drumhead, as hereinafter set forth, 10 reference being had to the accompanying drawings, wherein—

Figure 1 exhibits my design in section. Fig. 2 is a face view of a boiler-drumhead of elliptical contour, of which Fig. 1 would be a section.

15 Similar letters of reference indicate like parts.

The design exhibits two cylinders A B, the cylinder B being smaller than the cylinder A, with an intermediate flange C. The meeting angles of the flange C with the cylinders A and B are rounded or curved, as shown at E and F. The contour of the said cylinders is approximately elliptical, as shown in Fig. 2. 20 25

I claim—

The design for a boiler-drumhead substantially as herein shown and described.

HORACE SEE.
